(57) **CLAIM**

The ornamental design for a sanitizing station, as shown and described.

DESCRIPTION

FIG. 1 is a perspective view of a first embodiment of a sanitizing station;

FIG. 2 is a perspective view of a second embodiment of a sanitizing station;

FIG. 3 is a perspective view of a third embodiment of a sanitizing station;

FIG. 4 is a perspective view of a fourth embodiment of a sanitizing station;

FIG. 5 is a bottom view of the sanitizing station of FIGS. 1 to 4;

FIG. 6 is a rear view of the sanitizing station of FIGS. 1 and 2;

FIG. 7 is a front view of the sanitizing station of FIG. 1;

FIG. 8 is a front view of the sanitizing station of FIG. 2;

FIG. 9 is a side view of the sanitizing station of FIGS. 1 and 2 with the left and right side views being identical;

FIG. 10 is a top view of the sanitizing station of FIGS. 1 and 2;

FIG. 11 is a rear view of the sanitizing station of FIGS. 3 and 4;

FIG. 12 is a front view of the sanitizing station of FIG. 3;

FIG. 13 is a front view of the sanitizing station of FIG. 4;

FIG. 14 is a side view of the sanitizing station of FIGS. 3 and 4 with the left and right side views being identical; and,

FIG. 15 is a top view of the sanitizing station of FIGS. 3 and 4.

The broken lines are included for the purpose of illustrating portions of the sanitizing station that form no part of the claimed design. The column portion of the sanitizing station shown in FIGS. 1-4, 6-9, 11-14 is shown broken away in order to indicate that a specific height of this portion forms no part of the claimed design.
